UNITED STATES PATENT OFFICE.

NUMA L. AUCOIN, OF DELCAMBRE, LOUISIANA.

DESIGN FOR A PORTABLE FIREPLACE.

51,295.

Specification for Design.

Patented Sept. 25, 1917.

Application filed June 29, 1917. Serial No. 177,812. Term of patent 7 years.

To all whom it may concern:

Be it known that I, NUMA L. AUCOIN, a citizen of the United States of America, residing at Delcambre, in the parish of Iberia and State of Louisiana, have invented a certain new, original, and ornamental Design for Portable Fireplaces, of which the following is a specification, reference being had therein to the accompanying drawing, wherein—

Figure 1 is a front elevation of a portable fire place, showing my new design;

Fig. 2 is a rear elevation;

Fig. 3 is a side elevation;

Fig. 4 is a top plan view;

Fig. 5 is a bottom plan view;

Fig. 6 is a front elevation of the portable fire place the front thereof removed, also disclosing my new design.

I claim:

The ornamental design for a portable fire place as shown.

In testimony whereof I hereunto affix my signature.

NUMA L. AUCOIN.
